C. E. Richards.

United States Patent Office.

CELIUS E. RICHARDS, OF NORTH ATTLEBORO, MASSACHUSETTS.

Letters Patent No. 65,833, dated June 18, 1867.

IMPROVED PAPER BRAID.

The Schedule referred to in these Letters Patent and making part of the same.

TO ALL PERSONS TO WHOM THESE PRESENTS SHALL COME:

Be it known that I, CELIUS E. RICHARDS, of North Attleboro, in the county of Bristol, and State of Massachusetts, have made an invention of a new and useful or improved "Paper Braid" or "Band," composed of a series of paper threads or strands interwoven or interlocked together, the same constituting a new article of manufacture to be used in making hats, bonnets, lamp-mats, and various other articles; and I do hereby declare the nature thereof to be fully set forth in the following specification, and the accompanying drawing to exhibit a band, strip, or piece of braid, made in accordance with my invention.

In such drawing, A denotes the band or braid, and a a a a, &c., the series of paper strands or threads.

The object I have had in view in making my invention, is to produce a cheap and durable article, which can be applied to various useful purposes, as, for instance, in manufacturing hats, bonnets, &c., in imitation of straw, and is a good substitute therefor.

In carrying out my said invention, or forming a band or braid of any given width, I take a suitable number of strands of what is known in commerce as "paper twine." These strands or "paper twine" may be of any desirable color or colors, such as fancy may dictate. Having determined the number of strands requisite to make the band or braid of the desired width, the said strands may be braided together either by hand or by a braiding machine, or if desirable, the said band may be woven; but I prefer to manufacture it by means of a braiding machine.

My said invention cannot only be used as a good substitute for straw in the manufacture of many articles for which straw is used, but it can be afforded for about one-fourth the price of straw. I do not confine my invention to any particular number of strands, or to any particular form of the strands, nor to any particular form of braid or band, as these may be varied without changing the character of my invention.

Having thus set forth the nature and object of my invention, I would remark that I do not claim a cord, thread, or twine made of paper; but what I do claim, is as follows:

I claim, as a new or improved article of manufacture, a "braid" or "band," composed of a series of "paper threads" or strands united together, and to be used as and for the purposes set forth.

CELIUS E. RICHARDS.

Witnesses:

E. R. PRICE,

H. M. DAGGETT.
